OPERATOR FOR WINDOWS WITH SWINGING SASH

Axel W. Ahlgren, Rockford, Ill., assignor to Amerock Corporation, Rockford, Ill., a corporation of Illinois

Application July 18, 1956, Serial No. 598,638

1 Claim. (Cl. 268—105)

This invention relates to a window operator such as may be used for awning type windows in which the sash is mounted on the window frame to swing about a horizontal axis extending along the upper edge of the sash. More particularly, the invention relates to an operator with two horizontal arms pivotally mounted on the frame to swing together and apart and joined to the lower edge of the sash to open and close the latter upon such swinging. The arms are joined to the sash by a connection which permits the arms to slide back and forth along the lower sash edge.

The general object of the invention is to provide an operator of the above character with a new and improved connection between each arm and the sash which connection is durable in service use, is comparatively simple in construction and easy to manufacture and permits the arms and the sash to be detached when desired.

A more detailed object is to form each connection from a plastic cylindrical shoe which is mounted on the outer end of the corresponding arm and slides in a horizontally disposed cylindrical channel on the lower edge of the sash.

A further object is to mold the shoe integrally in a novel manner with a bracket which, in turn, is mounted on the arm.

The invention also resides in the novel construction of the connection between the bracket and the arm so that the bracket may be detached from the arm and also to permit the bracket and hence the shoe to swivel relative to the arm.

Other objects and advantages of the invention will become apparent from the following detailed description taken in connection with the accompanying drawings, in which

Figure 1 is a fragmentary perspective view of an awning type window incorporating the novel operator of the present invention.

Fig. 2 is an enlarged fragmentary sectional view taken along the line 2—2 in Fig. 1.

Fig. 3 is a fragmentary perspective view of the outer end of one of the arms.

Fig. 4 is a plan view of the bracket and the shoe.

Fig. 5 is a perspective view of the bracket and the shoe.

Fig. 6 is a sectional view taken along the line 6—6 in Fig. 4.

Fig. 7 is a sectional view taken along the line 7—7 in Fig. 4.

Fig. 8 is a perspective view of the bracket.

As shown in the drawings for purposes of illustration, the invention is embodied in an operator 10 for opening and closing the sash 11 of an awning type window. As is well known in the art, the sash is pivotally mounted on the frame of the window to swing about a horizontal axis extending along the upper edge of the sash so that the lower edge may be moved toward and away from the sill 12 of the frame.

The operator 10 includes a pair of elongated horizontal arms 13 whose inner ends are pivotally connected

to the casing 14 of the operator so that the arms swing about upright axes. The casing is fastened to the sill 12 and the arms are turned about their axes by a handle 15. The latter is connected to the arms by suitable gearing which is disposed within the casing and it may be of the type shown in my copending application Serial No. 598,637 filed July 18, 1956. The gearing is such that the arms swing in unison but in opposite directions.

The outer ends of the arms 13 are joined to the lower edge of the sash 11 by a connection 16 which permits the ends of the arms to slide laterally back and forth along the sash. When the arms are swung toward each other as shown in broken lines in Fig. 1, they push the bottom edge of the sash 11 out thus opening the window. As the arms are swung apart toward the position shown in full lines in which the arms are aligned and are parallel with the sash, the latter is drawn closed.

In accordance with the present invention, the connections 16 between the arms 13 and the sash 11 are arranged in a novel manner to permit easy opening and closing of the window, to facilitate detaching the arms from the sash and to provide a simple and inexpensive construction. Generally, the connections include an elongated horizontal channel 17 which is attached to the bottom edge portion of the sash 11 and which receives a shoe 18 (Fig. 2) that slides back and forth in the channel. There is a shoe on the end of each arm 13 and each shoe is mounted on a bracket 19 which is pivoted on the outer end of the arm to permit the shoe to turn relative to the arm as the shoe slides in the channel.

Herein, the channel 17 is a sheet metal stamping with a downwardly projecting flange portion 20 (see Fig. 2) which is attached to the sash by means of screws 21. The channel proper is cylindrical, describing an arc of somewhat more than 180 degrees and opening downwardly, and it extends transversely along the central portion of the sash near the lower edge thereof.

Each bracket 19 is generally L-shaped, having a horizontal leg 22 and an upright leg 23, and a shoe 18 is secured to the latter leg. In the present instance, the shoe is cylindrical in shape and is formed of molded plastic such as nylon. To secure the shoe to the leg, perforations 24 (Figs. 7 and 8) are formed in this leg along its upper edge. The shoe is molded directly onto the leg, the nylon flowing through the perforations so that the shoe is attached rigidly to the leg.

In order to detachably connect the bracket 19 to the outer end of the arm 13, a small post 25 upstanding from the end portion of the arm projects through a hole 26 (Fig. 5) in the leg 22. A latch member 27 in the form of a sheet metal plate with a downturned finger piece 28 is pivotally attached to one edge portion of the leg 22 by a pin 29. The plate is formed with a notch 30 which opens toward the post. Thus, the plate may be swung forward to place the post within the notch. In this position (illustrated in Fig. 7) the plate projects in under the head 31 of the post and thus prevents the bracket 19 from being lifted off the post. The plate is held in the latched position by a detent 32 which is in the form of an ear struck down from the plate and which snaps into a hole 33 in the leg 22.

As the sash is swung open, the outer ends of the arms 13 are raised somewhat and this results in a slight upward bowing of the arms. To permit such bowing, each bracket 19 is mounted on the end of the corresponding arm 13 for a limited amount of universal swiveling. Such swiveling is achieved by giving the extreme outer end portion 34 of each arm a spherical shape and by making the hole 26 in the leg 22 somewhat larger than the post 25. With this arrangement, the leg is free to rock in any direction on the spherical end portion 34 as illustrated in Fig. 7.

It will be observed that the use of the cylindrical chan-

nel 17 and the cylindrical shoes 18 not only permits the latter to slide endwise in the channel but also allows the shoes to turn relative to the channel as the window sash 11 swings in and out. Being made from a plastic such as nylon, the shoes slide freely in the channel and have good wear characteristics. At the same time, the shoes are securely attached to the bracket 19 since they are molded directly onto the leg and through the perforations. If it is desired to detach the sash from the arms, such as may be desired when washing the window, this may be effected easily simply by snapping back the latch plates 27 and lifting the brackets 19 off the posts 25.

I claim as my invention:

An operator for a window having a frame and a sash mounted on the frame to swing about an axis extending along one edge of the sash, said operator comprising a support adapted to be attached to said frame, two elongated arms pivotally connected at one end to said support to swing toward and away from each other in a plane parallel to said axis, the outer end portions of said arms having spherical contours, manually operable means for swinging said arms in unison but in opposite directions, an elongated member adapted to be secured to the free edge portion of said sash and having a cylindrical surface extending lengthwise of the member, a plate having a hole

therein, a shoe attached to said plate, said shoe having a cylindrical surface mating with the surface on said member to slide back and forth on the member, a post projecting outwardly from the spherical portion of one of said arms and through said hole and having an enlarged head, a latch element mounted on said plate to move toward and away from a latching position and having a slot receiving said post when in the latching position, said slot being narrower than said head to prevent said plate from being removed from said post, a second post on the spherical portion of the other of said arms, a second and similar plate and latching member mounted on said post, and a shoe attached to said second plate and slidably mating with said member, said plates swiveling on said spherical portions.
